UNITED STATES PATENT OFFICE.

CHARLES W. MORRIS, OF TOLEDO, OHIO, ASSIGNOR OF ONE-HALF TO WILBUR D. McBRIDE, OF TOLEDO, OHIO; MARY O. McBRIDE EXECUTRIX OF SAID WILBUR D. McBRIDE, DECEASED.

SWITCH-OPERATING MECHANISM.

1,031,082.

Specification of Letters Patent.

Patented July 2, 1912.

Application filed July 22, 1910. Serial No. 573,318.

To all whom it may concern:

Be it known that I, CHARLES W. MORRIS, a citizen of the United States, and a resident of Toledo, in the county of Lucas and State 5 of Ohio, have invented a certain new and useful Switch-Operating Mechanism; and I do hereby declare the following to be a full, clear, and exact description of the invention, such as will enable others skilled 10 in the art to which it appertains to make and use the same, reference being had to the accompanying drawings, and to the figures of reference marked thereon, which form a part of this specification.

15 My invention relates to railway switches, and has particular reference to switches of the class adapted to be operated from an engine or car traveling over the track in which the switch is disposed without stopping the engine or car for such purpose.

20 The object of my invention is the provision of a simple, improved and highly efficient mechanism of this class, which is easily operated from an engine or car while in motion and has its switch parts normally locked against an accidental or malicious moving of the same, and, which, during a switching operation, is operative to first release the locking means and then to actuate the desired switching movement of the switch parts.

25 Further objects of the invention will be apparent by reference to the following description.

30 35 The invention is fully described in the following specification, and while, in its broader aspect it is susceptible of embodiment in numerous forms, a preferred embodiment thereof is illustrated in the accompanying drawings, in which,

35 Figure 1 is a plan of the portion of a track with which the switch tripping means of my invention is associated with a trip-shoe in operative engagement therewith.

40 Fig. 2 is a plan of the switch mechanism of the invention and associated track, with a portion broken away. Fig. 3 is a longitudinal section of the tripping means taken on the line 3, 3 in Fig. 1, with a portion of an engine in section thereover and carrying the co-operating trip parts, one of which is depressed in switch throwing position and partly broken away. Fig. 4 is a section on the line 4, 4 in Fig. 3. Fig. 5 is a section 45 on the line 5, 5 in Fig. 2, and Fig. 6 is a side

elevation of Fig. 5 taken from the left side thereof.

Referring to the drawings, 1, 1 designate the two rails of a main track, and 2, 2 the rails of a side track branching therefrom. 60 The switch points 3, 3, one of which forms a part of each set of rails 1 and 2, are secured to a switch-block 4, which underlies the track rails at the point of jointure of the two tracks, and is suitably guided for longitudinal movements transversely of the track by a guide part 5, which rises from a base block 6. In order to enable the switch-points 3, 3 to have yielding movements longitudinally of the block 4 and relative to 65 the major portion thereof to permit a movement of such points by the flanges of the wheels of an engine or car running in the direction in which such points are directed, the points are attached to a yieldingly movable 70 portion 4^a of the block, as shown in Fig. 2. This portion is movable longitudinally of the block and has its ends thrust against coiled compression springs 4^b, which are mounted in recesses in the end portions of 75 the block and have their outer ends thrust against the outer ends of such recesses. Plates 4^c cover the springs.

80 The switch-block 4 has a rack-bar 7 preferably secured to the side thereof which is opposed to the direction in which the rails of the switch points 3, 3 extend and meshes with the segmentally toothed end 8 of an oscillatory arm 9. This arm is pivoted for horizontal swinging movements to a pair of vertically spaced cross-bars or plates 10, which are securely mounted beneath the rails at the side of the block 4 to which the rack-bar 7 is secured, and such arm has its outer end attached to links or rods 11, 11, which extend in opposite directions therefrom beneath the associated rails 1 and attach at their outer ends to the bell-crank levers 12. The levers 12 are mounted on associated 85 shafts 13, which are mounted at their ends 90 in the end portions of the bars or plates 10. The other arm of each lever 12 attaches to an associated draft-member 15, which member continues along the sides of the track 1 95 away from the switch-points 3, and, at a suitable distance from the switch, attaches to a bell-crank lever 16, which is carried by a frame 17, or in any other suitable manner, at the associated side of the track, as shown 100 in Fig. 1. 110

A guide-bar or strip 18 is carried by the frame 17 between the two rails 1, 1 in parallelism therewith and coöperates with suitable subjacent frame parts 19 (see Figs. 3 5 and 4) to form bearings for a pair of horizontally oscillatory blocks 20 and 21, which are spaced longitudinally of such bar. These blocks are of quadrant form and are adapted to be swung to one side or the other of the 10 bar 18, as indicated. The block 20 has a draft chain or member 22 attached to its outer end and extended in opposite directions therefrom with its ends attached to the free arms of the respective bell-crank levers 15, 16, 16, thus adapting an oscillation of the block 20 to rock one or the other of said levers. It is apparent that a rocking of either lever 16 communicates a shifting movement in one direction or the other to 20 the switch block 4 through the medium of the associated draft-member 15, bell-crank lever 12, rod 11, rock-arm 9 and rack-bar 7.

In order to lock the switch block 4 against being accidentally or maliciously moved to 25 throw the switch, a pawl or catch finger 23 is pivoted to the guide part 5 adjacent each end thereof and projects inwardly in position for its inner hooked end to engage the coöperating one of a set of catch-lugs 24 on 30 the adjacent side of the switch block 4 near the center thereof when such coöperating lug is at the limit of its movement with the block 4 in the direction of its pawl. Springs 25 act on the pawls to normally hold them 35 in lug engaging positions. The noses of the pawls 23 are attached by links 26 to associated bell-crank levers 27, carried by vertical shafts 28 mounted in the plates 10, 10 and these levers are connected by rods 29 to the 40 respective bell-crank levers 30, 30 mounted on the shafts 13 at the associated side of the track 1. The other arms of the levers 30 are connected by draft-members 31 to the bell-crank levers 32, which are suitably carried 45 by the frame 17 at the respective sides of the track 1, as indicated in Fig. 1. The levers 32 are in turn attached to the outer ends of a chain or draft member 33, which attaches adjacent its center to the outer end 50 of the block 21, thus adapting an oscillation of such block to communicate a lug-releasing movement to one or the other of the pawls 23.

The means which coöperates with the 55 blocks 20 and 21 to actuate the switch throwing or pawl releasing movements of their respective mechanisms is shown in the present instance as being carried beneath the cab of an engine, which is designated 34, but may, 60 of course, be carried by any other vehicle adapted for running upon a railway or like track. The means which I have illustrated for this purpose comprises a pair of elongated shoes or blocks 35, 35, which extend 65 longitudinally of the track and are hung

from associated levers 36 by links, which links pivotally attach to the central top portions of such shoes. The levers 36 extend longitudinally of the engine or car 34 and pivotally attach at their rear ends, as at 37, 70 to a bar or frame 38 secured to the under side of the engine cab floor 39, and each attaches adjacent its forward end to a foot-rod 40 which projects upwardly through the frame 38 and floor of the engine cab and 75 carries a foot plate 41 at its upper end. A spring 42 is mounted on each rod 40 and contacts with the frame 38 and plate 41 to retain the rod 40 and attached lever normally elevated. U-bars 43 depend from the frame 38 and have their horizontal portions projecting loosely through openings 44 in the shoes 35 adjacent their ends, and serve to limit the vertical movements of the shoes, as is 80 apparent.

When a lever 36 and shoe 35 have been lowered by a depression of the foot-rod 40 it is held in such position by a pawl 45, which is pivoted to the frame 38, as at 46, and has its lower end positioned to engage 90 over the notched free end of the lever, as shown in Fig. 3, the pawl being drawn into such engagement by a contraction spring 47, which connects the pawl to the forward U-bar 43.

In order to effect an automatic release of the pawl 45 from engagement with a lever end to permit a raising of such lever and its shoe 35 when the shoe has passed the trip-blocks 20 and 21, I mount a vertically disposed rock-arm or lever 48 on a shaft 49 in advance of the pawl and attach the upper and lower ends of such arm to the pawl by chains or flexible members 50 whereby an oscillation of the arm 48 in either direction 100 from normal position will pull one or the other of the members 50 and move the pawl to release the lever end. At a predetermined point in the track is disposed a cam-block 105 51 (see Fig. 2) which is adapted to coact with the lower end of the arm 48 and effect an oscillation thereof when it passes there-over, whether the engine be running forward or backward. The shoes 35, when lowered 110 pass between the bar 18 and a coöperating guide bar or flange 52 rising from the frame 17 at either side thereof as shown in Figs. 1, 3 and 4, and act upon the blocks 20 and 21 to swing them to one side or the other of the bar 18. The shoes 35 have both ends 120 tapered as at 35' to facilitate their coaction with the blocks 20 and 21.

To enable the switch-block 4, to be thrown by hand, if desired, it is provided at one end with a longitudinally extending arm or 125 bar 53 having rack-teeth 54 on its under surface with which a segmentally toothed disk or member 55 may mesh. The disk 55 is fixed to a shaft 56, which is journaled in an end portion of a rock-frame or treadle-mem- 130

ber 57. This rock-frame has its carrying shaft 58 journaled for vertical oscillatory movements in standards 59 rising from an end portion of the base-block 6 at an end 5 of the switch block, and has its outer end, or that opposed to the disk 55, held normally elevated due to the weight of the disk 55, and provided with a foot-plate or bar 60. Upon a depression of the outer end of the 10 frame or treadle member 57 the toothed portion of the disk 55 is raised into mesh with the rack-teeth 54, whereby a rocking of such disk effects a shifting of the switch-block 4 in one direction or the other. A 15 hand-lever 61 is adapted to be removably engaged with a flattened portion 62 of the shaft 56 for rocking such shaft.

As it is necessary to release the engaged pawl 23 from its lug 24 before the switch-block 4 can be shifted, I extend an arm 63 upwardly from the shaft 58 of the frame 57 and connect it, by wires or other suitable draft members 64, 64, to the bell-crank levers 66, 66, which levers are mounted on 25 shafts 67, 67 journaled in the plates 10 adjacent the inner ends of the respective pawls 23, 23 and are connected with the inner ends of such pawls by the wires or draft members 68, 68 as shown in Figs. 2 30 and 5. It is thus apparent that upon a depression of the outer end of the frame 57 the levers 66, 66 are simultaneously rocked to effect a release of the engaged pawl 23 from its lug 24.

35 The operation of my improved switch controlling mechanism is as follows: Should the main track be open and it be desired to switch an advancing train upon the said track 2, the engineer on such train depresses the 40 left foot-rod 40 in the cab, thus lowering the forward end of the attached lever 36, which moves the associated shoe 35 into position to pass between the guide bar 18 and the co-operating guide bar or flange 52 to the 45 left thereof. As the shoe 35 passes between such guide bars, its nose successively moves into contact with the alining portions of the blocks 21 and 20 and oscillates them to the positions shown in Fig. 1. 50 The oscillation of the block 21, communicates a lug releasing movement of the pawl 23 disposed at the left of the switch block 4, thus leaving the switch block free to be moved to shift the switch points. 55 The movements of the block 20 actuates the attached draft member 22, bell-crank lever 16, draft member 15, bell-crank lever 12, and rod 11, which parts are disposed at the left of the track, to rock the arm 9 to cause 60 its toothed end 8 to coat with the rack-bar 7 on the switch block 4 to move such block to the right whereby to move the switch points 3, 3 to close the main track and open the siding 2, as shown in Fig. 2. When the 65 switch block is shifted to such position the

pawl 23 to the right engages the associated lug 24 on the switch block and holds such block against further movements until the pawl has been released for such purpose. It is apparent that if the switch parts are in 70 the position shown in Fig. 2, to move the same to open the main track, it is only necessary for the engineer to depress the right hand shoe 35 so that it will engage and oscillate the blocks 20 and 21 to the left, thus 75 acting on the right hand pawl 23 to release it from locking engagement with the switch block 4 and actuating the switch-block throwing parts to move such block to the left. If it is desired to work the switch 80 by hand the operator engages a hand lever with the shaft 56, depresses the outer end of the frame 57 with his foot so as to elevate the toothed disk 55 into mesh with the rack-bar 53 and then oscillates the lever to 85 rock the disk 55 and throw the switch-block 4 in the desired direction. When either shoe-carrying lever 36 on the engine is depressed to move its shoe into block engaging position the pawl 45 engages the free end 90 of such lever to retain it in depressed position. When the engine has passed the blocks 20 and 21, the lower end of the rock-arm 48 coacts with a cam-block 51, disposed between the rails of the track, and is moved thereby to effect a release of the pawl 45 from engagement with the lever 36, thus 95 permitting the shoe to rise from block engaging position.

I wish it understood that my invention is 100 not limited to any specific construction or arrangement of the parts except in so far as such limitations are specified in the claims.

Having thus described my invention, what 105 I claim as new and desire to secure by Letters Patent, is,—

1. The combination with a track and a set of switch points associated therewith, of a switch member attached to said points and movable transversely of the track, said member having a toothed portion, an arm capable of oscillation in a horizontal plane having a segmentally toothed portion in mesh with the toothed portion of said member, an oscillatory element associated with the track at a predetermined distance in advance of said switch member, connections between said element and arm for imparting oscillatory movements from one to the other, and means movable over the track and having parts operative to selectively engage and move said element to impart a predetermined switching movement to the switch member. 110

2. The combination with a track and a set of switch points therefor, of a switch member attached to such points and movable transversely of the track, a rack-bar carried by such member, an oscillatory arm having a segmentally toothed portion in 115 120 125 130

mesh with said rack-bar, a horizontally oscillatory element associated with the track at a point in advance of said arm, connections between said element and arm for communicating oscillation therefrom in either direction to said arm, a member movable over the track, and trip means carried thereby, said trip means having a pair of parts which are selectively movable to co-

5 act with said element to impart oscillation in either direction thereto.

3. The combination with a track and switch points thereof, of a member attached to the switch points and movable transversely of the track, a mechanism operative to shift such member in either direction and having a trip part associated with the track at a distance from such member, a mechanism operative to lock such member in either 10 position of its shifting movement and having a trip part associated with the track at a distance from said member and a horizontally oscillatory locking part associated with said member, a vehicle movable over such 15 track, and mechanism carried by said vehicle and having parts selectively operative to act on said two trip parts to successively move said locking mechanism to release said member, and said shifting mechanism to 20 shift said member in a predetermined direction.

4. The combination with a track and the switch points, of a member attached to such points and movable transversely of the track, 25 a shifting mechanism for said member having a horizontally oscillatory trip part associated with the track at a distance from such member, a mechanism operative to automatically lock said member in shifted position 30 and having a horizontally oscillatory part associated with said first mentioned part, a vehicle movable over the track, and mechanism carried by such vehicle and operative with said parts to successively release the 35 engagement of the locking mechanism with said member and to actuate the shifting mechanism to shift said member in a predetermined direction.

5. The combination with a track and the switch points thereof, of a member attached to said points and shiftable transversely of the track, a mechanism operative to effect a shifting of said member in either direction of its movement and having a trip part associated with the track at a distance from 45 said member, pawls coacting with said member to lock it in shifted position, mechanism operative to release said pawls from engagement with said member and having a member 50 associated with said first mentioned part, a vehicle movable over the track, means carried by such vehicle and operative to coact

with said parts, to first actuate the pawl moving mechanism to release the engagement of the pawls with said member and 55 then to actuate the member shifting mechanism to shift such member in a predetermined direction.

6. The combination with a track and the switch points thereof, of a switch block attached to such switch points and movable transversely of the track, mechanism operative to shift such block in either direction of its movement and having a trip part associated with the track at a distance from such 70 block, a mechanism operative to automatically lock said block in shifted position and having a trip part associated with the track at a distance from such block, a member movable over the track and a mechanism carried by such member and having a pair of shoes selectively movable to cooperate with said parts, one shoe to move said parts in one direction and the other shoe to move said parts in the other direction whereby to 75 actuate the locking mechanism to release its engagement with the block and the block shifting mechanism to shift the block in a predetermined direction.

7. The combination with a track and the switch points thereof, of a member attached to such switch points and movable to shift the same to open and close the track, said member having a rack-bar associated therewith, means for locking said member in shifted position, and mechanism normally disengaged from said rack-bar and movable to engage such rack-bar and to shift the position of said member and also to release said locking means from engagement with the member.

8. The combination with a track and the switch points thereof, of a member attached to such switch points and movable to shift the same to open and close the track, said member having a rack-bar projecting from an end thereof, means for automatically locking the member in shifted position, a rock-frame, a pinion carried by such frame and movable by a rocking of the frame to mesh with such rack-bar, means for rocking said pinion, and means connecting said locking means and rock-frame for effecting a release of the locking means from engagement with said member when said frame is rocked to move its pinion into mesh with the rack-bar.

In testimony whereof, I have hereunto signed my name to this specification in the presence of two subscribing witnesses.

CHARLES W. MORRIS.
